UNITED STATES PATENT OFFICE.

GEORGE R. DAVIS, OF MARLBORO, MASSACHUSETTS.

FLOOR CART.

1,427,583.

Specification of Letters Patent. Patented Aug. 29, 1922.

Application filed September 16, 1921. Serial No. 501,169.

To all whom it may concern:

Be it known that I, GEORGE R. DAVIS, a citizen of the United States, residing at Marlboro, in the county of Middlesex and 5 State of Massachusetts, have invented certain new and useful Improvements in Floor Carts, of which the following is a specification.

This invention relates to propellable devices for facilitating scrubbing or working on floors and particularly to such devices which, while so constructed as to keep the worker clean and dry, are readily portable. Such a device I designate a "floor-cart."

15 Devices of this character have been proposed heretofore but so far as I am aware the constructions are not such as to provide the greatest ease to the worker, nor are they splash-proof. The object of the present invention is to provide a splash-proof floor-cart which is so constructed as readily to be carried from place to place as may be required. A further object of the invention is 20 to provide a floor-cart which gives the greatest comfort in a kneeling posture, while at the same time permitting the worker easily to propel it by pressure of the toes on the floor or other surface being worked on.

To the accomplishment of these objects 30 the invention comprises the features and combinations of parts hereinafter described and then particularly pointed out in the appended claims.

The preferred form of the invention is 35 illustrated in the accompanying drawings in which Figure 1 is a perspective of the floor-cart ready for use; Fig. 2 is a rear elevational view with the sides collapsed; Fig. 3 is a rear elevational view with the 40 sides raised and partly in section; and Fig. 4 is a sectional view on the line 4—4 of Fig. 3.

In the embodiment of the invention illustrated in the drawings a rectangular base 45 frame is formed of two flat side pieces 6 and 8, a front piece 10 and a rear piece 12, which are secured together at the corners in any suitable or convenient manner. Within the two side pieces 6 and 8, and secured thereto, are two longitudinal stiffeners 14 and 16 which conveniently may be shaped as shown on Fig. 4, i. e. with a horizontal lower edge and an oblique upper edge, sloping downwardly from the rear to the front of 50 the cart. These stiffeners serve as supports for the floor 18 and also provide sufficient

bearing surface for the ball-bearing casters 20, of which there are four, one at each corner of the base frame.

Hinged to the side pieces 6 and 8 are 60 side or splash-boards 22 and 24 and a similar splash-board 26 is hinged to the front piece 10. It will be observed that the height of the front piece 10 is less than that of the side pieces so that when the front splash-board 26 is folded down, as in Fig. 2, it will lie below the level of the upper edges of said side pieces (see dotted lines Fig. 4). The side splash-boards when folded down will then lie flat on the folded down front splash-board. The entire cart is so designed that the splash-boards are of ample height to fully protect the clothing, yet they are less than half the width of the cart, so that when the entire device is collapsed it presents a 70 comparatively flat article that can easily be carried under the arm. Fasteners of a convenient form such as the hooks and screws 28 (dotted lines Fig. 3), are provided to maintain the splash-boards in their 80 raised position when the cart is in use.

A soap-holder 30 may be hinged to one frame side piece and held in horizontal position by a latch 32. This holder is folded down, as shown in Fig. 2, when the cart is 85 to be transported. A cushion 34 is placed loosely on the kneeling-floor, and this may be packed in the open space beneath the floor when the cart is collapsed for transportation purposes.

90 Particular attention is directed to the sloping kneeling-floor 18. It is important that the floor of the cart be as near the surface to be worked upon as possible to obviate strain in leaning over to reach said surface. Since 95 the cart is to be propelled by the toes, the ankle is at a fixed height and higher than the desired position of the floor of the cart. If the kneeling-floor 18 is made horizontal the weight of the worker's body is supported 100 wholly by the knees causing excessive strain and discomfort. In the present invention, however, the kneeling floor is sloped to such an extent that when the worker kneels on the cushion 34 the entire lower leg is pressed 105 upon and supported, thus sustaining the body weight without excessive strain. The height of the rear edge of the kneeling-floor is such that the toes are in position to engage the floor, or other surface, and be used 110 as the cart propelling agent. In commercial practice the cart will be made in different

sizes and proportions to meet all requirements.

The advantage of the high splash-boards will be apparent to all housewives and the 5 convenience of the collapsing feature is particularly important to scrub women who find it necessary to carry the cart from place to place. From the foregoing description it will be understood that the floor-cart may be 10 used to advantage not only for scrubbing, painting or finishing floors, but also may be used in laying tile floors and the like.

The nature and scope of the present invention having been indicated and the preferred embodiment of the invention having 15 been specifically described, what is claimed been specifically described, what is claimed as new, is:—

1. A floor-cart comprising a rectangular base frame, a kneeling-floor supported there- 20 by forming a hollow bottom to said frame, folding splash-boards on three sides of said frame, a cushion receivable on said floor when the splash-boards are raised and within the hollow bottom when the splash-boards 25 are folded down, a soap holder hinged on

said frame for folding thereagainst when the cart is to be transported, and means for retaining the soap-holder in position to hold soap when the cart is in use.

2. A portable floor-cart having a box-like 30 frame comprising four walls, a kneeling-floor rigidly supported within said frame below the top edges of the side walls and the front wall to thereby form cushion abutments above the kneeling-floor and also form 35 a four-wall open cavity below the kneeling-floor, a cushion adapted to be removably supported on the kneeling-floor and abut said abutments when thereon and to be removable therefrom and inserted in the afore- 40 said cavity below the kneeling-floor when the cart is to be compacted, and splash-boards hinged respectively to the upper edges of 45 said abutments and adapted to fold inwardly upon the kneeling-floor when the aforesaid cushion is removed therefrom, means being provided for detachably locking the adjacent edges of the splash-boards together when erected for use.

GEORGE R. DAVIS.
